ELECTRIC DISCHARGE TUBE

Hubert Wendlik, Prague, Czechoslovakia, assignor to Westinghouse Electric & Manufacturing Company, East Pittsburgh, Pa., a corporation of Pennsylvania

Application May 11, 1938, Serial No. 207,200
In Czechoslovakia May 18, 1937

4 Claims. (Cl. 176—50)

My invention relates to discharge devices and especially to the container of such discharge devices.

An object of the invention is to provide a discharge device having a container that is especially resistant to strong electric, chemical, and thermal effects in the vicinity of the electrodes.

Another object of the invention is to utilize ceramic material in the container walls of the discharge device.

Other objects and advantages of the invention will be apparent from the following description and drawing, in which:

Fig. 1 is a view in cross-section of a discharge device illustrating an embodiment of the invention in the container wall adjacent the electrode.

Figs. 2, 3, 4, 5, 6, 8, and 9 are figures in cross-section that are modifications of the embodiment of the invention in Fig. 1.

Figs. 7 and 10 are cross-sectional views of a discharge device disclosing modifications of the invention applied to the complete container.

It is generally known that that part of the discharge tube where the electrode is located is made from glass.

In developing the tubes it was found that the glass parts in the vicinity of the electrode are subject to strong electric, chemical, and thermal effects. Especially the hot electrodes, such as an incandescent cathode, necessitate the protection of the glass parts located close to them.

Such protection is achieved by increasing the distance between the glass and the electrode by enlarging the tube so as to form a spherical shape and locating the electrode in the center.

Or, a screening is made between glass and electrode, consisting of metal or insulating material.

Finally, there is a design using special glass or gas-tight ceramic materials that are resistant to the above mentioned influences.

An increase of the distance between glass and electrode offers the disadvantage that the shape of the discharge tube has to be changed in a way which makes it less efficient and desirable.

The use of screening is undesirable because it is difficult to securely support the screening parts. These screens and supports occupy much space, and special brackets are required, which makes the design too complicated.

Special glasses increase the price of the tube because of higher priced material and manufacturing costs; besides, they are only partly satisfactory.

As it was already mentioned, gas-tight ceramic materials are used too, and they do not require special sealing.

It is known that ceramic materials are much more resistant to electric, chemical, and heat action in the space of discharge than glass.

Up to now the choice of these materials has

been limited, because the materials that were most satisfactory from a manufacturing standpoint were not gas-tight.

According to the present invention, the above mentioned disadvantages are overcome by replacing the glass in the proximity of the electrode by a ceramic material which is made gas-tight by special sealing materials.

The following have been found to be the best sealing materials: enamels, metal surfacing, varnishes, impregnation (for example soaking in oils, waxes, fats, oils of a low evaporating pressure) and liquids.

The choice of a sealing material depends on the type of the discharge tube and on the conditions in which it is to operate. As an example, mercury would be a suitable sealing material for tubes containing mercury.

When enamels are used, it is advisable to apply them on the outside of the tube, in order to avoid exposure in the discharge space.

The metal coating for sealing is applied by the electroplating process; also by spraying and by dipping into a metal bath good results can be obtained.

The current leads to the electrodes are led through the ceramic material and are sealed by the sealing coating itself or by special glass particles.

When enamel or metal coating is used, it is advisable, if no special sealing is added, to make it stronger at those points where the current leads are located.

When fusing ceramic material with glass, it is desirable that the fusing surfaces of these materials should be especially porous.

The fusing can be done by using intermediate layers of special glass or by using one or more intermediate metal layers.

In Figs. 1 through 10 of the drawing, I have illustrated several possible applications of the invention. In Fig. 1 I have illustrated diagrammatically an electrode 5 supported on the current lead 6. This electrode may take any desired form of the prior art including the type of hot electrode previously mentioned that necessitates the protection of the walls located close to it. The electrode 5 is enclosed by a cup-shaped ceramic body 3 that is sealed by fusion to the glass wall of the vessel or container 1 at the point of sealing or fusion 2. A coating 4 of enamel, metal coatings, or varnish, is applied to the outside surface of the ceramic cup-shaped body 3 by any of the means previously mentioned. The lead or leads 6 pass through the ceramic material as disclosed.

In Fig. 2 the cup-shaped ceramic body has a projection or rim 1 that protrudes into the glass vessel 1 and has lateral extensions for making the seal 2 with the glass vessel 1. The special advantage of this shape is that the ceramic pro-

section 7 is intermediate the seal 2 and the discharge path terminating on the active face of the electrode 5.

In Fig. 3 a still further modification is disclosed in which the ceramic projection 7 into the vessel 1 has an enlarged conical shape 8 that acts to concentrate the discharge towards the active surface of the electrode 5. The lateral projection from the ceramic body in this modification makes the seal 2 with the laterally extending body of the glass portion of the vessel instead of the lateral ceramic extension being bent at right angles in Fig. 2 to make a seal with the tubular portion of the container. It will be noted that the enamel, metal coating, or varnish is made stronger at the exterior part 9 where the current lead passes through the ceramic material.

In Fig. 4 I have disclosed a modification of the invention in which the ceramic body 3 has a tube-shaped prolongation extending upward from the bottom of the cup to support within its enclosure the electrode 5. This arrangement protects against heat losses. The sealing is done by means of enamel, metal coating, or varnish. Additional glass particles 11 are utilized for sealing the current lead or leads where they pass through the ceramic body.

In Fig. 5, the modification discloses in place of the diagrammatically illustrated electrode 5, an electrode 5 comprising an inner metal coating on the ceramic body. The current lead or leads 6 pass through the ceramic body and are first protected by a thickened portion of the sealing enamel, metal coating, or varnish 4 and then by cement contained in a base 12.

In Fig. 6 I have disclosed the inner metal coating 5 similar to the coating 5 in Fig. 5 but it does not have the current lead 6 through the ceramic material. The outer coating 4 in this figure is of metal which combines in combination with the inner metal coating 5 on the other side of the ceramic material to form a condenser with the inner coating as an electrode. The ceramic material in this modification preferably has a higher dielectric content. As is known, some ceramic materials can be manufactured with a dielectric constant more than forty times higher than that of air. This arrangement makes it possible to have a very small electrode of a size that would not be possible when only glass is utilized.

In Fig. 7, I have disclosed an application of the design in Fig. 1 to both ends of the tube so that they constitute a complete container for a discharge device. An opening 16 is located in this modification at the place of the fusing seam 2 and can be used as tubulation or for any other purpose desired. The sealing on the exterior of the ceramic portion is accomplished by means of the enamel, metal coating or varnish previously mentioned. If a metal coat is utilized, it should, of course, be interrupted by the insulating sealing material so that there will be no path between the two leads 6 over the outer surface of the container.

Fig. 8 illustrates a modification in which the electrode 5 is not completely enclosed by the ceramic portion 3, but in which the electrode 5 partly protrudes into the glass tubing 1. The sealing is made with enamel, metal coating, or varnish 4 as previously mentioned.

Fig. 9 shows a design where electrode 5 is located entirely within the glass vessel 1 and is supported by a tubular piece 10, which widens in the direction of the discharge and protects the electrode and the glass against thermal action.

Spiral rod 14, secured by cement 13, protects the leads 6, which pass through rod 14 and are soldered at the end 15.

Fig. 10 shows a case where two electrodes 5 are located in a ceramic body 1. The ceramic body has no current leads and constitutes the discharge tube. Another ceramic body 3, which has current leads and electrodes 5, closes the discharge tube. The sealing is done by means of enamel or metal coating or a varnish 4. When metal coating is used, it should be interrupted by insulating sealing material.

It will be noted that the various embodiments of the invention disclosed in the drawing provide a container wall of ceramic material adjacent the electrode or electrodes that is especially capable of withstanding strong electric, chemical, and thermal effects. In particular, the lateral extensions from the ceramic portion for the purpose of sealing to the glass portion of the vessel, provide a protection to the seal by the interposition of the rim of the ceramic portion between this seal and the discharge path. The conical shape of the rim in Figs. 3 and 9 provide means for concentrating the discharge towards the active surface of the electrode. The dielectric strength of a ceramic material permits the condenser electrode, illustrated in Fig. 6. Many modifications of the invention will, of course, be apparent to those skilled in the art from the foregoing description and the numerous embodiments illustrated. It is for this reason that the electrode 5 in most of the illustrations has been only diagrammatically illustrated because the invention can be adapted to fit in with the many structures disclosed in the prior art.

What is claimed:

1. An electric discharge device comprising a container having a cup-shaped ceramic portion, a conductor passing through and in contact with the ceramic bottom of said cup-shaped ceramic portion, and an electrode within said cup-shaped ceramic portion connected with said conductor, said container having another portion adjacent said cup-shaped ceramic portion sealed thereto, said cup-shaped ceramic portion having its rim projecting past the sealed connection of said two portions to within said other portion.

2. An electric discharge device comprising a cup-shaped ceramic portion, an electrode within said cup-shaped ceramic portion, a connection to said electrode passing through and in contact with the ceramic bottom of said cup-shaped ceramic portions, a lateral extension from said cup-shaped ceramic portion, and a container wall sealed to said lateral extension.

3. An electric discharge device comprising a cup-shaped ceramic portion, an electrode within said cup-shaped ceramic portion, a connection to said electrode passing through and in contact with the ceramic bottom of said cup-shaped ceramic portions, a lateral extension from said cup-shaped ceramic portion, and a container wall sealed to said lateral extension, and a gas-tight coating on the exterior of said ceramic portion.

4. An electric discharge device comprising a container having a cup-shaped ceramic portion, an electrode within said cup-shaped ceramic portion, a lead for said electrode, a lateral extension from said cup-shaped ceramic portion, and a wall of said container sealed to said lateral extension, said cup-shaped ceramic portion having a projecting conical rim.
